UNITED STATES PATENT OFFICE.

THOMAS McGOVERN, OF NEW YORK, N. Y.

EMBORESSED FABRIC FOR DECORATING WALLS, &c.

SPECIFICATION forming part of Letters Patent No. 325,687, dated September 3, 1885.

Application filed May 7, 1885. (No specimens.)

To all whom it may concern:

Be it known that I, THOMAS McGOVERN, a citizen of the United States, and a resident of the city, county, and State of New York, have 5 invented certain Improvements in and relating to Embossed Fabrics for Decorating Walls, &c., of which the following is a specification.

My invention relates to compound embossed fabrics designed, primarily, for ornamentation; and my object is to produce a fabric with figures in prominent relief and of a solid character, and with very little loss of material.

My fabric is not limited in its application, but it is designed to be employed for all purposes where embossed textile fabrics are required. I contemplate making my fabric in strips, which I denominate "molding," and I will describe my fabric as constructed in this manner.

20 The ordinary "quilling" designed to be used as a trimming is usually constructed of two strips of textile material, the face fabric being usually silk or satin and the backing fabric a thin coarse material, sometimes called 25 "buckram" or "wigging." These strips are superimposed and passed between suitably-corrugated rolls, whereby the figures in relief are formed in the fabric, being thrown up on the face and hollow at the back. A strip of 30 this fabric will lose from thirty to forty per cent. in length by embossing, and the margins of the strip, which should be plain and smooth, will be plaited. This plaiting makes it necessary, or, at least, desirable, to stitch the edges 35 of the strip after embossing to secure the plaits or folds.

I am able to produce by my invention a strip of molding with quilling or other ornamentation in relief that will be as long, or substantially so, after the embossing as it was before, and thus effect a material saving in the linear measurement.

In the drawings which serve to illustrate my invention, Figure 1 is a plan view of a 45 strip of quilling or molding made in accordance with my invention. Figs. 2 and 3 are transverse sections of same, taken, respectively, in the planes indicated by lines 22 and 33 in Fig. 1. Fig. 4 is a plan view similar to 50 Fig. 1, showing the raised figures of a pattern different from that in Fig. 1. Fig. 5 is a trans-

verse section of the molding with its under surface made slightly concave, as it may be, if desired. Fig. 6 is a longitudinal section of the molding.

Let *a* represent a thin face fabric of some textile material—as silk, satin, or sateen, for example—and *b* a back fabric of some thick soft felted material. I usually employ a thick wool felt, but the character and thickness of the backing may vary somewhat. A soft paper felt would serve the purpose. The strips are superimposed, and then, by preference, stitched along their edges, as seen at *c c*. I now emboss this compound strip by any of the 65 well-known mechanical devices employed for this purpose, producing on the surface the figures *d* in relief and the parts *e* in intaglio. The back of the compound fabric is usually left smooth or uncorrugated, the elevations 70 and depressions being produced in the compression of the felted backing *b*. I may, however, form depressions in the back of the fabric under the figures in relief, especially where the relief is considerable or pronounced. In 75 any case the compression of the parts *e* appears to compact the felt by lateral pressure into or under the raised grooves *d*. Thus the raised figures of the face fabric *a* will have below or back of them a cushion of felt or 80 other soft material, which fills the cavity produced by embossing.

In some cases, especially where a high relief is desired, the backing may be made concave in the embossing process, as seen in Figs. 85 5 and 6.

I usually stitch the fabrics together at *c c* before embossing, but it may be done after embossing. The margins of the strips will be left smooth and level, and not crimped or plaited, as in the ordinary quilled fabric. In the ordinary mode of making quilling the stitching cannot be done satisfactorily before embossing for the reasons before given—that is to say, the stitching must be done after the embossing, in order to properly secure the plaits in the margins which result from the surplusage due to the loss in length by embossing. I lose but a very small percentage in this way, and therefore have no plaits in the 95 margins.

In carrying out my invention I usually size

the felt backing when it requires it in order to give it the desired stiffness; but this is not essential.

I have shown the molding made in a single strip; but this is not essential. Several strips may be made in one piece and afterward separated. The stitching is not absolutely essential, but it serves to hold the plies of fabric together.

o The figures in relief may vary indefinitely. In Fig. 1 the design is similar to that known as "quilling," but leaves, flowers, and geometrical designs may be made as well. Fig. 4 shows one design differing from Fig. 1.

5 Having thus described my invention, I claim—

1. As an improved article of manufacture, a compound fabric composed of a face fabric of thin textile material and a back fabric of thicker soft material, said compound fabric having figures formed in relief on its face, substantially as set forth.

2. As an improved article of manufacture, a strip or molding of textile material, substan-

tially as described, having figures in relief 25 formed on its face, and smooth or unplaited margins, as set forth.

3. As an improved article of manufacture, a fabric composed of a face fabric of thin textile material and a back fabric of thicker felted material, said fabric having figures formed in relief on its face, as described, and a substantially smooth and level back, the raised figures being solid, substantially as set forth.

4. As an improved article of manufacture, 35 a molding consisting of a face fabric, *a*, of thin textile material and a back fabric, *b*, of thicker felted material, in the form shown, superimposed and stitched at the edges and having figures *d* in relief formed on the face by embossing, substantially as set forth.

In witness whereof I have hereunto signed my name in the presence of two subscribing witnesses.

THOMAS McGOVERN.
